UNITED STATES PATENT OFFICE.

FREDERICK M. FURBER, OF REVERE, MASSACHUSETTS, ASSIGNOR TO UNITED SHOE MACHINERY CORPORATION, OF PATERSON, NEW JERSEY, A CORPORATION OF NEW JERSEY.

COATING APPARATUS.

Application filed August 9, 1923. Serial No. 656,564.

To all whom it may concern:

Be it known that I, FREDERICK M. FURBER, a citizen of the United States, residing at Revere, in the county of Suffolk and 5 State of Massachusetts, have invented certain Improvements in Coating Apparatus, of which the following description, in connection with the accompanying drawings, is a specification, like reference characters on 10 the drawings indicating like parts in the several figures.

This invention relates to apparatus for applying to various objects a coating substance, as for covering with blacking or 15 other stain the peripheral portions or sides of shoe-heels. It is more particularly adapted for operating upon heel-bases to which are attached rubber lifts.

In the use of heel-blacking machines for 20 the purpose just indicated, there is presented the problem of spreading upon the heel-wall a substantially uniform coating between definite lines, determined by the rand-crease at one side and the junction between 25 the base and lift at the other, without overrunning upon either the shoe-upper or the lift, the application to the side of the heel near the rand-crease being further complicated by the fact that the horizontal 30 ledge of the heel must also be blacked. Objects of my invention are to so organize the brush or other applying member and its associated position-determining members, as 35 those elements which vary the relations between the applying members and the work by acting either upon an applying member to change its arrangement or upon the work to locate it with respect to the applying 40 members, that the results outlined are attained. Moreover, there is provided a highly efficient organization for actuating the applying members and supplying the coating substance thereto.

Of the several forms which my improved 45 apparatus may assume, one is illustrated in the accompanying drawings, in which—

Fig. 1 is a front elevation, with parts in section;

Fig. 2 is an end elevation looking from 50 the right in Fig. 1;

Fig. 3 is a top plan view;

Fig. 4 is a vertical sectional detail

through the applying and gage members and more closely associated parts; and

Fig. 5, a detail, partly in section, of the 55 stripping device for the feeding disk.

The frame 10, with its receptacle 12 for the blacking or other substance which is to be applied to the work, together with some of the minor devices, generally resembles 60 those of the crest heel blacking machine, which is the subject of patent No. 1,025,523, Furber, May 7, 1912, and need not here be described. In the frame is journaled horizontally a main driving shaft 14 extending 65 from the front to the rear and joined by a worm and worm-wheel 16 to a transverse intermediate shaft 18. This latter shaft is geared at 20 to a section 22 of an operating shaft, which turns in a bearing transversely 70 of the apparatus at the front of the frame. Connected to the section 22 by a universal coupling 24 is a second section 26, forming an angle with its companion section. That is, the portion 26 is out of axial alinement 75 with the portion 22, it being inclined downwardly with respect to the horizontal from the coupling. The section 26 is journaled in a bearing 28 supported by a thumb-screw 30 threaded into a bracket 32 carried upon the 80 frame, this thumb-screw passing through the L-slot 34 of a bayonet-joint. This connection allows the applying member and its associated elements, which are actuated by the section 26, to be removed readily for 85 cleaning. The separation of this removable section from the section 22 is permitted by the manner of joining the coupling 24 to the section 26, the former carrying a projection 90 36, which enters a slot 38 in the shaft, they separating upon longitudinal displacement of the latter. The bracket 28 is shown as secured to the frame by a screw 40 passing through a slot 42 in the bracket, this slot lying substantially at right angles to the 95 axis of the shaft-section 22. The function of this screw-and-slot connection will be described later.

Secured about the inner extremity of the shaft-section 26 is a sleeve 44 having, at its 100 end adjacent to the coupling 24, a plate in the form of an attached disk or an annular integral flange 46. Abutting against this plate is the body 48 of an applying brush,

the bristles or other fibers of which are situated in close proximity to the inner wall of the plate. The outer portion of the sleeve 44 is threaded at 52 to receive an internally threaded collar 54, which, contacting with the brush-body, clamps it in place against the plate. The exterior of the collar is also threaded to receive the internally threaded hub of a dished disk 56, the concave side of which is toward the brush. The edge of the disk is shown as lying somewhat outside the circumference of the plate 46, both of these being within the outer extremities of the brush-fibers which furnish the applying surface. Movement of the disk along the sleeve, it being secured at the point to which it is adjusted by a set-screw 57 threaded through the hub, allows of a different degree of compression to be obtained by the contact of the disk. This forces the outer portions of the fibers against the plate, without interference with the adjustment by engagement of the disk with the fixed base-portions. The extreme outward adjustment is shown in dotted lines in Fig. 4 of the drawings. This permits the effective width of the applying surface to be varied to adapt it to operate over heel-bases of different heights, there remaining in the fibers a capacity to bend laterally on account of the projection of the ends beyond the peripheries of the plate and disk. At the side of the brush where the uncoated portion of the work is without the protection of the gage-disk, this bending is made less than at the guarded side, because of the greater radial extension of the disk 56. The flexing of the fibers, which are preferably rather soft, permits the coating substance to be applied without spattering, and tends to brush it out laterally, so that an accumulation of the coating along the outer edge will not be produced. This is of especial importance at the lower portion of the base, where it contacts with an attached rubber lift.

Fixed upon the inner end of the shaft-section 22, near the coupling 24, is a concave disk 58 having a rim-portion 60 extending in a direction substantially at right angles to the axis. The lower rim-portion is closely adjacent to the side of the brush-fibers 50, there preferably being, however, a slight separation to prevent an excessive application of the coating substance along this line. The relation between the disk 58 and the brush may be altered by movement of the bearing 28 upon the bracket 32, this movement being provided for by the shifting of the slot 34 along the screw 30. The edge 60 of the disk is adapted to enter the rand-crease of a shoe S, the heel-base H of which is to be blacked. To this heel-base is shown attached, this occurring prior to the blacking operation, a rubber lift L.

The disk 58 acts as a guide or gage for the work, causing it to be held in the correct relation to the brush for this to apply the coating substance across the side of the base to the extreme upper portion, at the same time protecting the upper. The gage-disk also tends to advance the work past the brush, assisting the operator in this movement. Adjustment of the bracket 32 laterally of the axis of the shaft-section 26 by means of the screw-and-slot connection at 40, 42 alters the relation of the applying surface of the brush to the gage-edge of the disk, so that when the latter is in place in the rand-crease, said brush will act to the best advantage over the outer surface of the base, giving the desired flexing of the fibers, without putting too much pressure upon these. This position of maximum efficiency may be maintained by this adjustment as the brush wears in use.

The coating substance is supplied from the receptacle 12 to the brush by a rotatable device, including a sleeve 62 fixed upon the shaft 18 and having oppositely extending arms 64, 64. Attached to the extremities of these arms are series of closely placed fingers 66, the two sets of fingers being staggered with respect to each other, so that they, in combination, operate over a practically continuous line. As the fingers revolve in the direction of the arrow in Fig. 2, they dip into the coating substance in the receptacle, and, upon leaving this, pass through the ends of the fibers 50 outside the peripheries of the plate 46 and disk 56. This supplies the necessary amount of the substance to the applying surface of the brush. Because of the angle which the shaft-section 26 carrying the brush forms with the section 22, from which it receives its rotation, the portion of the brush-fibers receiving the coating substance from the fingers diverges from the disk 58. Consequently, while, at the opposite side the disk and brush are closely associated, at the feeding point they are quite widely separated, so the fingers may act upon the brush without interference with the disk. The feeding device has another function. The fingers are curved forwardly in the direction of rotation, and have upon the fibers a combing action which, when they tend to become matted under the pressure of the work against them and the gathering of the coating substance, causes their rearrangement by straightening and separating them. Preferably, the peripheral speeds of the brush and fingers are different, so that the line at which the fingers act angularly about the brush is varied, causing them to operate over the entire applying surface. The sleeve 62 has at its inner side a flange 68, to which is attached a feed-disk 70 provided with a substantially radial rim-portion 72 movable

in close proximity to the inner face of the rim 60 of gage-disk 58. This rim 72 turns in the coating substance in the receptacle 12, and transfers this to that portion of the disk 58 which contacts with the ledge of the heel. The substance is therefore fed to the applying rim 60 to cause it to coat this ledge-portion at the same time that the fibers 50 coat the side of the base. To establish the proper feeding relation between the disks 70 and 58, the shaft-section 22 is adjustable longitudinally, so that the applying surface of the rim 60 may be caused to approach or retreat from the feeding surface of the disk 70. To provide for this, the shaft has, outside its bearing, collars 74, 74, which may be adjusted upon it to vary the longitudinal position of the shaft. This adjustment occurs without disturbance of the gearing 20 through elongation of the gear-teeth at 76, while play in the connections of the coupling 24 prevents interference with the connected shaft-section 26. The depth of the layer of the coating substance upon the feeding surface of the disk 70, and therefore the amount supplied to the disk 58, is determined by a stripper-plate 77, which contacts with the feeding portion 72 of the disk 70. The plate is mounted upon a spindle 78 movable longitudinally through a sleeve 80 threaded into an opening in the frame and held variably in position by a set-screw 82. Transversely through the spindle, with its extremities projecting through slots 84 in the sleeve, passes a pin 86, and between this pin and a collar 88 fast upon the sleeve is a helical spring 90. This spring exerts its force to thrust the stripper-plate yieldably toward the feeding disk. The extent of this movement may be changed by a collar 92 threaded upon the outer end of the spindle 78, this collar contacting with the sleeve 80. Adjustment of the collar so alters the relation between the contact-surface of the plate 77 and the feeding surface of the disk 70 that a film of the coating substance of the desired thickness may be carried upon the latter and transferred to the applying surface upon the rim 60. Yieldable scrapers 94, 94 operate upon the outer side of the disk 58, as in the patented machine previously referred to, keeping clean the surface over the shoe-upper.

In employing my improved machine to coat, as with blacking, the heel-base H upon the shoe S, without having this blacking overrun, either upon the upper of the shoe or upon the attached rubber lift L, a brush is placed upon the shaft-section 26, the width of the applying surface of the fibers 50 of which brush approximates the height of the heel-bases to be operated upon. To cause the applying surface to act most effectively, brushing the blacking out smoothly without passing over the line between the base and lift, the disk 56 may be adjusted, this, by its contact with the outer sides of the fibers, differently compressing them. The operator then, starting at the junction between the side of the heel and the breast, applies the rand-crease to the disk-rim 60, turning the shoe in the opposite direction to that in which the disk rotates, so that the points of engagement of the rim 60 and the applying surface of the brush are gradually shifted along the heel until the opposite line between the side and breast is reached. During this travel of the shoe, the fibers 50 receive the blacking from the receptacle 12 by means of the fingers 66 and are straightened by said fingers, while the gage-disk is supplied over its side contacting with the ledge of the heel by the disk 70. Consequently, both the side and ledge-surfaces are coated. On account of the separation between the brush and the rim 60, the application of the blacking to the side of the heel, along the line of the ledge, is prevented from being excessive, while at the bottom of the side, adjacent to the rubber lift, the adjustment of the disk 56 causes the fibers to accurately follow the surface of the base, and to work the coating out uniformly. During this operation, the upper is effectively shielded by the body of the disk 58. The direct connection of the shaft-sections assures a constant speed of rotation between the brush and gage-disk, and this actuation, in spite of the angular relation between the sections, is effected by simple gearing.

Having described my invention, what I claim as new and desire to secure by Letters Patent of the United States is:

1. In a coating apparatus, a rotatable applying brush having a wall for contact with its fibers at one side and at the opposite side a member adjustable toward and from the wall to vary its contact with the fibers, the wall and contact member leaving the applying ends of the fibers free to bend.
2. In a coating apparatus, a rotatable applying brush having a wall for contact with its fibers at one side and at the opposite side a contact member, means arranged to vary the position of the wall and brush, and means arranged to vary the relation between the brush and contact member.
3. In a coating apparatus, a shaft, a plate mounted thereon, a brush carried by the shaft adjacent to the plate, and a concave disk contacting at its periphery with the brush at the side opposite the plate.
4. In a coating apparatus, a shaft, a disk fixed to the shaft, a brush surrounding the shaft and abutting against the disk, a collar holding the brush against the disk, and a disk adjustable upon the collar toward and from the brush.

5. In a coating apparatus, a shaft, a disk fixed to the shaft, a brush surrounding the shaft and abutting against the disk, a collar cooperating with the brush, and a concave disk threaded upon the collar and contacting at its periphery with the brush.
6. In a coating apparatus, a gage member for contact with the work, a brush adjacent thereto, and means at the side opposite the gage member arranged to vary the effective position of the fibers of said brush.
7. In a coating apparatus, a gage member for contact with the work, a brush adjacent thereto, and a member movable in contact with the fibers of the brush at the side opposite the gage member and toward and from said gage member.
8. In a coating apparatus, a gage member for contact with the work, a brush adjustable toward and from the gage member, and means at the opposite side of the gage member from the brush arranged to vary the effective position of the fibers of said brush.
9. In a coating apparatus, a member having an applying surface consisting of fibers, and a member acting to arrange the fibers and to supply a coating substance thereto.
10. In a coating apparatus, a rotatable brush, a comb co-operating with the brush, and means for supplying a coating substance to the comb.
11. In a coating apparatus, a rotatable brush, a rotatable comb engaging the brush, and a receptacle for a coating substance in which the comb rotates.
12. In a coating apparatus, a rotatable brush, a rotatable applying disk associated with the brush, a rotatable comb engaging the brush, a feeding disk co-operating with the applying disk, and a receptacle for a coating substance in which the comb and feeding disk rotate.
13. In a coating apparatus, a plurality of shaft-sections connected to transmit motion from one to another, such sections lying at an angle to one another, and applying members carried by adjacent sections and having portions in proximity to each other.
14. In a coating apparatus, a plurality of shaft-sections connected to transmit motion from one to another, such sections lying at an angle to one another, a gage member carried by one shaft-section for contact with the work, and an applying member carried by an adjacent section.
15. In a coating apparatus, a plurality of shaft-sections connected to transmit motion from one to another, such sections lying at an angle to one another, a gage member carried by one shaft-section for contact with the work, an applying member carried by an adjacent section, said gage member and applying member being in proximity to each other at one side of the shaft and diverging therefrom, and means for supplying a coating substance to the more widely separated portions of the members.
16. In a coating apparatus, a shaft-section, an adjacent-shaft-section, means for applying power to rotate one of the sections, a universal coupling connecting the sections, and a gage-disk and an applying brush carried by the respective sections.
17. In a coating apparatus, a shaft-section, an adjacent shaft-section lying at an angle thereto, a universal coupling connecting the sections, a disk mounted upon one section, a brush mounted upon the other section, said disk and brush diverging from closely adjacent portions of their peripheries, and independent means for supplying a coating substance to the more widely separated portions of both the disk and brush.
18. In a coating apparatus, a plurality of shaft-sections connected to transmit motion from one to another, applying members carried by the sections, and means arranged to vary the relation between the applying members.
19. In a coating apparatus, a plurality of shaft-sections connected to transmit motion from one to another applying members carried by the sections, and means arranged to vary the position of one of the shaft-sections laterally of its axis.
20. In a coating apparatus, a shaft-section, an adjacent shaft-section, means for applying power to rotate one of the sections, a universal coupling connecting the sections and permitting movement of one of said sections laterally of its axis, a gage-disk and an applying brush carried by the respective sections, and means arranged to differently position laterally of its axis the shaft-section carrying the brush.
21. In a coating apparatus, a rotatable applying member, means arranged to vary the position of the applying member longitudinally of its axis, and means arranged to vary the position of the applying member laterally of its axis.
22. In a coating apparatus, a shaft, a bearing in which the shaft is rotatable, a support for the bearing, an applying member carried by the shaft, means arranged to fix the bearing in different positions upon the support, and means arranged to fix the support in different positions.
23. In an apparatus for coating heel-bases having attached rubber lifts, a rand-crease-gage, a rotatable brush co-operating therewith, and means arranged to vary the relation of the brush-fibers to the line between the base and lift.
24. In an apparatus for coating heel-bases having attached rubber lifts, a rand-crease-gage, a rotatable brush co-operating there-

with, means arranged to vary the relation between the gage and brush, and means arranged to vary the relation of the brush-fibers to the line between the base and lift.

25. In an apparatus for coating heel-bases having attached rubber lifts, a rotatable disk for engagement with the rand-crease, a brush rotatable adjacent thereto, and a disk adjustable in contact with the brush 10 with relation to the line between the base and lift.

26. In an apparatus for coating heel-bases having attached rubber lifts, a shaft having connected sections lying at an angle 15 to each other, a rand-crease-gage carried by one section, and a brush carried by the other section for operating upon the base.

27. In an apparatus for coating heel-bases having attached rubber lifts, a shaft 20 having connected sections lying at an angle to each other, a rand-crease-gage carried by one section, a brush carried by the other section for operating upon the base, and means mounted upon the last-mentioned 25 section for varying the relation of the brush to the line between the base and lift.

28. In an apparatus for coating heel-bases having attached rubber lifts, a shaft having connected sections lying at an angle 30 to each other, a rand-crease-gage carried by

one section, a brush carried by the other section for operating upon the base, and means mounted upon the last-mentioned section for varying the relation of the brush to the line between the base and lift while 35 maintaining its relation to the rand-crease substantially constant.

29. In an edge-blackening apparatus, a rotatable applying member, a blacking-feeding member delivering to the applying member, 40 a stripper co-operating with the feeding surface of the feeding member, a spring acting to force the stripper toward the feeding member, and means for adjustably limiting the movement of the stripper toward the 45 feeding member.

30. In an edge-blackening apparatus, a rotatable applying member, a blacking-feeding member delivering to the applying member, 50 a sleeve mounted adjacent to the feeding member, a spindle movable in the sleeve and carrying a stripper-plate co-operating with the feeding member, a spring surrounding the spindle and acting to force the stripper-plate toward the feeding member, and an 55 adjustable member fixed upon the spindle and contacting with the end of the sleeve.

In testimony whereof I have signed my name to this specification.

FREDERICK M. FURBER.
